UNITED STATES PATENT OFFICE.

BAYARD F. WRIGHT, OF WASHINGTON, DISTRICT OF COLUMBIA.

MAIL-BAG CATCHER.

No. 903,040.

Specification of Letters Patent.

Patented Nov. 3, 1908.

Application filed May 7, 1908. Serial No. 431,376.

To all whom it may concern:

Be it known that I, BAYARD F. WRIGHT, a citizen of the United States of America, residing at Washington, in the District of Columbia, have invented new and useful Improvements in Mail-Bag Catchers, of which the following is a specification.

This invention relates to mail bag catchers, and one of the principal objects of the same is to improve the latch and spring mechanism of the bag holder.

With the devices in use at present the mail bag is often dropped, owing to the failure of the fork catching the same. Moreover, the bag often becomes wedged into the crotch of the catcher, and in many instances the bag has to be mutilated in order to be detached. It is to overcome these defects in mail bag catchers that my invention is de-

signed.

The construction of my mail bag catcher is such that the pouches will not fall when once engaged.

In the accompanying drawing,—Figure 1 is a plan view of a mail bag catcher provided with my improvements and connected to the opposite sides of a car door opening. Fig. 2 is an enlarged longitudinal sectional view of the crotch portion of a mail bag catcher, showing my improvements in the two positions which they assume in use. Fig. 3 is a detail sectional view taken on the line 3—3 of Fig. 2, looking in the direction indicated by the arrow.

Referring to the drawing for a more specific description of my invention, the numeral 1 designates the door frame of a mail car, and pivoted to the keepers 2 on the outside of the door frame is the mail bag catcher 3 comprising the pivot bar 4 and the catcher bar 5. The shank 6 of the catcher is provided with a rubber gasket or buffer 7, and the usual handle 8 is provided for manipulating the catcher.

In the crotch of the catcher, in accordance with my invention, I secure a bow-shaped spring 9 which is seated in a recess in the crotch and secured in place by means of screws 10. The free end of the spring 9 is formed into a rounded bead 11. A latch 12 is pivoted at 13 and provided with a beveled end, said beveled end adapted to be seated in a recess 15 in the catcher. The opposite end of the latch 12 is rounded, as

To set the catcher in position to pick up the bag from a stationary crane the spring 9 engages the latch 12 at a point beyond its pivot 13, as shown in Fig. 1, and in dotted lines in Fig. 2. When the bag strikes the spring 9 the beaded end 11 of the spring is brought against the terminal end of the latch, and said latch is then swung upon the pivot 13 to the position shown in full lines in Fig. 2 to hold the bag in place between the spring and latch. By throwing the latch 12 to the dotted line position in Fig. 2, the spring 9 is withdrawn from the recess 15 by the point of the latch engaging behind the bead.

From the foregoing it will be obvious that a mail bag catcher provided with a latch and spring made in accordance with my invention will not permit the bags to be wedged in the crotch and will operate smoothly and efficiently under varying circumstances and conditions.

Having thus described the invention, what is claimed as new, is:—

1. A mail bag catcher comprising the usual fork, a spring secured in the crotch of the fork and provided with a rounded end, and a latch pivoted to the fork and provided with a bevel head, said fork having a recess therein for said head and the end of the spring.

2. A mail bag catcher provided with a spring secured to the crotch thereof, said catcher having a recess for the end of said spring, a latch provided with a beveled head and pivoted in said recess, whereby when the end of said spring extends beyond the pivotal point of the latch the latter is held longitudinally of the catcher and when a bag strikes the spring it throws the latch across the catcher to hold the bag.

3. A mail bag catcher comprising a spring secured in the crotch of the catcher, the latter having a recess for the end of the spring, and a latch provided with a beveled head pivoted in said recess and bearing against said spring.

In testimony whereof I affix my signature in presence of two witnesses.

BAYARD F. WRIGHT.
